UNITED STATES PATENT OFFICE.

HAROLD F. PENNEY AND CHARLES CLARK FRAUTZ, OF GENEVA, NEW YORK, AS
SIGNORS TO PHILLIPS & CLARK STOVE CO. INC., OF GENEVA, NEW YORK, A COR-
PORATION OF NEW YORK.

GRATE-BAR SUPPORT.

Application filed March 8, 1923. Serial No. 623,788.

To all whom it may concern:

Be it known that we, HAROLD F. PENNEY and CHARLES CLARK FRAUTZ, citizens of the United States, residing at Geneva, in the 5 county of Ontario and State of New York, have invented certain new and useful Improvements in Grate-Bar Supports, of which the following is a specification.

The object of this invention is to provide 10 a new and improved method and means for locking the grate bars of a furnace grate into their respective bearings in the grate bar supports.

These and other objects of this invention 15 will be fully illustrated in the drawing, described in the specification and pointed out in the claims at the end thereof.

In the accompanying drawings:

Figure 1 is a perspective view of a portion 20 of a grate showing the novel means of locking the grate bars in place in their supports.

Figure 2 is a detail vertical sectional perspective view of one of the grate 25 bars and its supporting bearing, the section being taken on the line 2^x—2^x of Figure 1.

Figure 3 is a detail perspective view of a portion of the supporting member of the 30 grate bars.

Figure 4 is a perspective view of the outer end of one grate bar.

Figure 5 is a perspective view of a portion 35 of the locking plate for locking the grate bars into their supporting bearings.

Figure 6 is an elevation of the locking plate shown partly in Figure 5.

Figure 7 is an elevation of the supporting member shown partly in Figure 3.

40 In the several figures of the drawings like reference numerals indicate like parts.

It is essential that the grate bars of a furnace grate are locked in place in their respective bearings or supports so that they 45 cannot disengage themselves from the support during their rotation for if this happens one or more of them will drop down at one or both ends and allow the fire or at least part of it to drop into the ash pit while the grate is being shaken down. This must be prevented.

In our present invention the locking of the grate bars to the grate bar support is secured by means of a locking plate which

when slipped over the grate bars and 55 properly positioned thereon holds the bars centered in place in the bearings in the grate bar support. Our invention also permits the easy removal of one or more of the grate bars and the insertion of new ones 60 in their place without disturbing the remaining grate bars.

As illustrated in the figures the grate bar support 1 for supporting the forward ends of the grate bars 2, 2 comprises a 65 horizontal bridge member having vertical ends with the bifurcations 3 and 4 formed thereon. These bifurcations rest on the pins 5 and 6 provided on the inner walls of the ash pit 7. Depending from the grate bar 70 support 1 are two pairs of hooked shaped bearing members having the bearings or cradles 8 and 9 formed thereon of which one projects toward the left and the other toward the right hand wall of the ash pit 75 7. The outer ends of the grate bars 2 are supported in these bearings or cradles 8 and 9 and rotate therein.

For the purpose of holding the grate bars 2 against endwise movement in these bearings or cradles a pair of collars or flanges 80 10 and 11 are formed on each of the grate bars which are spaced apart and located thereon so as to project down on each side of the bearings or cradles as illustrated in 85 Figures 1 and 2.

Besides the collars or flanges 10 and 11 each grate bar 2 is also provided with a pair of lugs 12 and 13. These lugs project 90 radially from the grate bar at right angles to each other. The locking plate 14 that will now be described is placed between the lugs 11 and 12 on the one side and collar or flange 10 on the other side.

For this purpose the locking plate 14 95 is provided with four holes 15 through which the ends of the grate bars 2 can pass. Surrounding each of the holes 15 is a collar 16 in which the radial slots 17 and 18 are provided. The slots are located at right 100 angles to each other although a greater or smaller angle would answer the same purpose providing the lugs 11 and 12 are correspondingly spaced and project from the grate bars so that they can pass thru the 105 slots. The sides of these slots are tapered and incline toward the outer face of the collar so as to provide a large opening for the

lugs 12 and 13 to enter into and then center these lugs in the slots 17 and 18 until they can pass therethrough.

In placing the locking plate onto the grate bars, it is necessary to first position all of the grate bars 2 so that the lugs 12 and 13 thereof stand in the same angular position as the slots 17 and 18 provided in the locking plate 14. In this way the lug 12 of the 5 grate bar is brought in line with the slot 18 in the locking plate and the lug 13 is brought in line with the slot 17. The locking plate is then slipped into place as above pointed out so that the locking plate and its collars 10 are located between the lugs 12 and 13 and the collars 15. The grate bars are then turned back to their normal position in which the lugs 12 and 13 are out of line with their corresponding slots in the locking 20 plate so that the locking plate cannot be slipped off again from the grate bars but is locked thereon and this in turn locks the grate bars to their support by holding them centrally of the bearings provided therein.

25 We claim:

1. In a supporting and locking means for grate bars the combination of a supporting member, bearings formed on said supporting member, grate bars adapted to rest in 30 said bearings, a lug projecting from each of said grate bars, a locking plate having a depression therein with a hole in the center thereof for each of said grate bars, the hole in each of said depressions having a slot leading 35 from it thru which the lug on each of said grate bars can pass, said grate bars with said lugs being adapted to pass thru the holes and the slots in said locking plate to make said lugs rotate on the outside of 40 said depressions in said locking plate during the rotation of said grate bars.

2. In a grate bar and support therefor, the combination of a supporting bridge, hook-shaped bearings formed on said bridge 45 and depending therefrom, grate bars adapted to rest in said hook-shaped bearings, a pair of collars formed on each of said grate bars, one at each end of said hook-shaped bearings to prevent an endwise movement 50 of said grate bars in said hook shaped bearings, a pair of radial lugs projecting from said grate bars with a space between said lugs and the outer one of said collars, a locking plate having depressions therein with a 55 hole in the center thereof and a pair of

radial slots leading from the holes, said locking plate being adapted to have said grate bars pass thru the holes for each of said grate bars and its radial lugs pass thru the slots in said depressions to the outside 60 of said depressions and make said lugs rotate on the outside of said depressions during part of the rotation of said grate bars.

3. In a grate bar and support therefor, the combination of a bridge, a fork depending from each end of said bridge, a pair of studs supporting the forked ends of said bridge, a pair of bearing members depending from said bridge and having a hook-shaped bearing at each side thereof, grate 70 bars adapted to rest in said hook-shaped bearings, a locking plate having a depression therein with a hole in the center thereof with a slot leading from the hole for each of said grate bars, a radial lug formed 75 on each of said grate bars, said locking plate being adapted to be placed over the ends of said grate bars with the grate bars projecting thru the holes in said depressions after said lugs have passed thru the 80 slots leading from the holes in said depressions so as to rotate outside of said depressions on the rotation of said grate bars, said locking plate being adapted to hold said grate bars in said hook shaped bearings 85 during their rotation.

4. In a supporting and locking means for grate bars, the combination of a supporting member, bearings formed on said supporting member, grate bars adapted to rest in 90 said bearings, a pair of collars formed on said grate bars and adapted to hold said grate bars against endwise movement in said bearings, a lug projecting from each of said grate bars, a locking plate having a 95 depression therein with a hole in the center thereof for each of said grate bars, the hole of each of said depressions having a slot leading from it, said grate bars with said lugs being adapted to pass 100 thru the holes and the slots respectively in said depressions of said locking plate and locate one of said collars of each of said grate bars in said depressions and allow said lugs to rotate on the outside of said depressions on the rotation of said grate bars. 105

In testimony whereof we affix our signatures.

HAROLD F. PENNEY.

CHARLES CLARK FRAUTZ.
